CLAIM

The ornamental design for a mailbox crown, as shown and described.

DESCRIPTION

FIG. 1 is a front perspective view of a mailbox crown, in use, showing my new design;

FIG. 2 is a front perspective view thereof;

FIG. 3 is a rear perspective view thereof, in use;

FIG. 4 is a side elevational view thereof;

FIG. 5 is a front elevational view thereof;

FIG. 6 is a top plan view thereof; and,

FIG. 7 is a top plan view thereof, in a flattened position.

All sides not shown in the drawing disclosure forms no part of the claimed design.

The broken line showing of a mailbox is included for the purpose of illustrating environmental structure and forms no part of the claimed design.
